UNITED STATES PATENT OFFICE.

JOHN F. BOYET, OF COVINGTON, KENTUCKY, ASSIGNOR OF ONE-HALF TO WALTER W. BURNS, OF WASHINGTON, DISTRICT OF COLUMBIA.

TOY.

Application filed November 29, 1921, Serial No. 518,578. Renewed May 25, 1927.

This invention relates to aerial toys and has for its primary object the provision of an improved arrow having a two part shaft, the upper shaft being separable from the lower shaft and forming a control member for a parachute, the latter being connected to the control member at its center and also having its corners connected to the opposite end of the control member.

10 Referring to the drawing wherein a preferred embodiment of my invention is illustrated,

Figure 1 is an elevation view of my improved arrow showing the parachute hanging as in position ready for ascension and showing the upper end of the lower shaft of the arrow in section.

Figure 2 is a view of the parachute during descent.

20 Figure 3 is a plan view of the bow used for propelling the arrow.

Figure 4 is a plan view of the top of the parachute when laid flat, the guys being disconnected from the lower end of the upper 25 shaft of the arrow.

10 designates the lower shaft and 11 the upper shaft of the arrow. The lower shaft is provided with a recess or notch 12 at its lower end, arranged adjacent the notch and 30 about the lower end of the shaft 10 are a series of feathering devices as bird feathers 13 for guiding the arrow in flight, in a well known manner. The upper end of the shaft 10 is provided with a socket 14 to receive the 35 lower end 15 of the upper shaft 11. The upper end of the shaft 10 is provided with a suitable soft annular member 16 which is made of any suitable material as rubber. This soft annular end projects slightly above 40 the top of the shaft 10 and is very useful as a marker when the lower section of the arrow is being used alone. When this lower section of the arrow is being used alone, chalk or paint may be placed on the edge of 45 the annular marker. When this marker strikes the target or object toward which the arrow is shot, a mark is left, which serves as a score indicator.

Secured to the top of the shaft 11 is the 50 center of a parachute 17 which is held in place by a ferrule 18. The parachute 17 is of any suitable equilateral shape, as square, and has attached to its corners guys 19 which hold the parachute in shape during 55 descent. The corner ends of the guys 19

are secured in position with relation to the lower end of the shaft 11, as to the cork weight 20 through which the shaft 11 extends.

The arrow when used with the parachute 60 may be propelled by a bow 21 having a string 22.

The arrow when in use with the parachute is preferably shot directly upward by means of the bow 21 and its string 22 in a 65 well known manner. As soon as the arrow stops its upward movement, the parachute immediately spreads, the upper shaft floats away from the lower shaft which latter turns and returns quickly to the ground. 70 The parachute attached to the upper shaft slowly returns to the earth.

It will thus be seen that I have provided a two part arrow which is provided with a parachute which will immediately open as 75 soon as downward flight begins and which has a shaft portion heavier at the bottom than at its top whereby the opening of the parachute is facilitated.

While I have described in detail an embodiment of my invention, I desire to have it understood that modifications and changes may be made without departing from the spirit of my invention and within the scope of the appended claims.

Having described my invention, what I claim is:

1. An arrow having a two part shaft, a 80 parachute, means securing the top of the parachute to the upper part of the shaft, the two parts of the shaft being axially arranged relative to each other and having a detachable connection therebetween, the upper part of the shaft being readily separable from the lower part thereof upon the 85 spreading of the parachute at the beginning of the descent, the upper part of the shaft being further constructed to fall to the 90 ground bottom first.

2. An arrow comprising a two part shaft 100 having upper and lower parts, a parachute having its body portion surrounding the upper part of the shaft and a detachable connection between the two parts of the shaft, the upper and lower parts of the shaft being readily separable from each other upon the spreading of the parachute at the beginning of the descent.

3. An arrow comprising a shaft having 105 upper and lower parts, a parachute having 110

its body portion surrounding and secured to the upper part of the shaft, and its periphery attached therebelow to the upper part of the shaft, the upper part of the shaft being so constructed as to be heavier at its lower end than at its upper end, the two parts of the shaft having a readily separable connection therebetween, the parts separating from each other upon the spreading of the parachute at the beginning of the descent.

4. An arrow comprising a two part shaft having upper and lower parts, a parachute having its body portion surrounding the upper part of the shaft and having its periph-

ery secured therebelow to the upper part of the shaft, the upper part of the shaft being so constructed as to be heavier at its lower end than at its upper end, a detachable connection between the two shaft parts and a guiding device at the lower end of the lower part, the connection being such as to readily permit the two parts of the shaft to separate upon the spreading of the parachute at the beginning of the descent.

In testimony whereof I hereunto affix my signature.

JOHN F. BOYET.
